UNITED STATES PATENT OFFICE.

DETLEF KARL HEINRICH SCHÜMANN, OF HAMBURG, GERMANY.

RESPIRATOR.

1,222,683.

Specification of Letters Patent. Patented Apr. 17, 1917.

Application filed December 8, 1913. Serial No. 805,847.

To all whom it may concern:

Be it known that I, DETLEF KARL HEINRICH SCHÜMANN, a subject of the King of Prussia, residing at 35 Rödingsmarkt, Hamburg, Germany, have invented certain new and useful Improvements in Respirators, of which the following is a specification.

My invention relates to a self-contained, preferably portable, respirator, which operates on the regeneration principle and serves, for example, to provide breathing air, that is to say, purify the used air for firemen or rescue parties, in rooms which are filled with injurious gases. According to the invention, the carbon dioxide and a part of the hydrogen, which is exhaled is removed by chemical means from the exhaled air and the latter, after the addition of new oxygen, is again returned to the person employing the apparatus. A closed cycle is maintained and none of the surrounding atmosphere is admitted into the system.

In such devices the parts which serve for regeneration must be changed from time to time, as the impurities from the breathed air accumulate in time and the chemicals take up a great deal of moisture which renders their renewal necessary. In order to render it possible in portable respirators to exchange at the place of action, the regenerating devices which serve for collecting the injurious elements contained in the exhaled air, it has been proposed to form the mouths of the containers which hold the chemicals so that when they are inserted in the air duct, check valves disposed in the duct are automatically opened by the action of abutments, while when the containers are removed the valves automatically close.

The arrangement has several disadvantages. In the first place, the insertion and removal of the regenerating devices and the pressing of the container mouths onto the tightening flanges of the ducts takes place under a double lever action which requires a special lock for safety in order to avoid the loosening and leaking of the joints.

The most essential disadvantage of the known arrangement, however, is that during the removal of the regenerating device, the air circulation is interrupted, which causes interruptions in the respiration ducts which render breathing very difficult, and in a short time, impossible.

According to the present invention, the valve members between which the exchange-

able container is arranged, are constructed in the form of a cap nut which is formed into a valve, such that when the nut is screwed onto the container mouth, the ducts 60 are opened and vice versa when the connection is loosened they are automatically closed. Therefore the connections can be made in the simplest manner without requiring a special lock device. 65

In order to avoid the occurrence of undue inner pressures when the regenerator containers are exchanged, the check valves may be formed as safety valves, so that at a certain pressure they establish a connection 70 with the outside atmosphere.

The valves are advantageously constructed in the general form of threaded caps which connect up the passage ways when they are screwed down on the air pipe connections (that is, in introducing the regenerating device into the apparatus) and interrupt the air pipe connections when they are unscrewed. 75

In order, furthermore, to maintain a circulation of the breathing air while exchanging the used up purifying device for a new one, inside of the room filled with noxious gases, one or more of the valves are constructed as double seat valves and in the act 80 of disconnecting the mouth of the purifying device, a by-pass is simultaneously established through which the breathing gases can pass around the purifying device. When the normal communication is reestablished 85 then inversely the branch conduit or by-pass is again cut out. 90

In the drawing,

Figure 1 shows a general diagrammatic view of the complete apparatus, and 95

Fig. 2 shows in enlarged scale the novel features.

The breathing mask 1 is connected by two tubes 2 and 3 with the air tank 4, which consists of two chambers separated from 100 each other by a partition wall 5. To the right hand chamber of tank 5 there is connected a pipe 6 which leads to the purifying device 7 and further through a cooler 8 back to the left hand chamber of the tank 4. 105 To the pipe 6, a branch tube 9 is connected near the purifying device 7, which branch tube 9 is connected through a safety-valve 10 and a reducing valve 11 with an oxygen tank 12. The oxygen tank is provided in 110 usual manner with a manometer 13. Between the conduits 6 and 9, a connection

14 is provided which lies in the axis of the vessel 7. The connecting of the vessel with the main air pipe is accomplished by means of removable screw threaded unions which 5 at the same time serve as valves. Such a union may comprise, for example, a cylindrical chamber 15, the cover 16 of which is slipped over the tubular end 17. The side wall of the cover 16 is provided with 10 perforations and its bottom 19 operates in conjunction with the mouth of the cylindrical chamber 15, which is constructed in the form of a valve seat. For connecting the cylindrical chamber 15 with the container 15 a screw flange 20 formed on the cover 16 coöperates with a correspondingly formed mouth piece 21 on the container.

The valve plate 19 carries a spindle 22 which extends into the interior of the tubular chamber 15 and upon it is fastened a 20 transverse plate or lug 23. A spring 24 surrounds the valve stem 22 and is compressed between the plate 23 and a perforated disk 25 fastened in the tube and 25 through which the stem 22 passes. This spring is so arranged that it tends to close the valve or hold it closed.

The upper valve, in the embodiment of the invention herein shown, is constructed 30 in the form of a double valve and the pertaining valve stem 22 carries in addition a plate 26, which operates upon the tubular chamber 15 and seats on the top thereof which is suitably formed to serve 35 as a valve seat.

In the open position of the valves, the connection between the purifying chamber 7 and the pipe 6 is maintained by means of the perforations 18. In screwing up the 40 unions on the mouth pieces 21, the plates 19 are lifted off their seats against the pressure of springs 24 and the valves thereby opened. At the same time, the plate 26 of the upper valve seats on the valve seat 45 27, so that an alternate opening and closing of the passage way affected by this double valve is accomplished.

The operation of the entire device is as follows:

50 When the purifying device is to be replaced, the two screw threaded caps are loosened and finally assume the position shown for the upper cap in the drawing. In this position communication of the air 55 pipe 6 with the outside air is prevented, even when the purifying device is removed, and a direct connection between the oxygen tank and the air pipe 6 (with the purifying device eliminated) is at the same time 60 produced by the opening of the valve 26, 27. Whereas the flow of the breathing gases

previously took place in the direction of the arrow A, this current now, after the cut out is effected by loosening the lower screw cap, takes place in the direction of 65 the arrow B. A circulation of the breathing gases occurs therefore in spite of the removal of the purifying device and at the same time it is made possible to provide against excessive inside pressure, as excessive pressure would lift the valve plates 19 off their seats against the pressure of spring 24. In introducing a new purifying chamber, the valves are opened by screwing on the threaded caps and the passage of gases 70 through the purifying device again takes place through the chambers 15 of the valves. As the valve 26, 27 is simultaneously closed, the fresh oxygen is forced to flow in the direction of the arrow A and to mix with 75 the breathed gas before it is passed through the purifying device.

I claim:

1. A respirator of the character described, comprising in combination a regenerator 85 having inlet and outlet mouths, conduits leading to and from said regenerator, cap nuts longitudinally movable on the ends of said conduits for connection with said inlet and outlet mouths, and spring pressed valve 90 members associated with said cap nuts for closing said conduits when in one position and adapted to open said conduits when in another position.

2. A respirator of the character described 95 comprising in combination a regenerator having inlet and outlet mouths, conduits leading to and from said regenerator, cap nuts longitudinally movable on the ends of said conduits for connection with said inlet 100 and outlet mouths, and valve members associated with said cap nuts, said cap nuts being constructed as valve members and also as safety valve members and having operating springs for holding them seated against 105 the ends of the said conduits against a limited interior pressure, and adapted to open said conduits when in another position.

3. A respirator of the character described, comprising in combination an air pipe, a 110 removable purifying device, an oxygen supply tank, a pipe normally connecting said tank with said air pipe, a by-pass, and connecting means for said purifying device having means for properly connecting said 115 oxygen tank through said by-pass and excluding outside air when the purifying device is removed.
